DESIGN FOR A BILLFOLD

Samuel J. Smallman, New York, N. Y.

Application February 2, 1944, Serial No. 112,412

Term of patent 7 years

(Cl. 87—3)

To all whom it may concern:

Be it known that I, Samuel J. Smallman, a citizen of the United States of America, residing in New York, county of New York, and State of New York, have invented a new, original, and ornamental Design for a Billfold, of which the following is a specification, reference being had to the accompanying drawing, forming part thereof.

Fig. 1 is a front perspective view of a billfold showing my new design.

Fig. 2 is a front perspective view of the billfold as shown in Figure 1, with the purse portion in open position.

The back of the billfold is substantially plain.

I claim:

The ornamental design for a billfold, substantially as shown and described.

SAMUEL J. SMALLMAN.
